TRAFFIC CONTROL SYSTEM

Denis Wright, Elm Vale, Liverpool, England, assignor, by mesne assignments, to Automatic Telephone & Electric Company Limited, London, England

Application April 28, 1934, Serial No. 722,893
In Great Britain May 19, 1933

7 Claims. (Cl. 177—337)

The present invention relates to traffic control systems for use at road junctions or the like and is more particularly concerned with systems of the type in which, in addition to the signals for indicating "go" and "stop", a caution signal is employed with is displayed between signal changes. The object of the invention is to control the display of the caution signal in such manner as to increase the factor of safety without causing undue delay at the crossing.

Though the invention is not limited to vehicle-actuated systems and could be applied equally satisfactorily to fixed time controllers, the following discussion of its use in a vehicle-actuated system will make clearer its precise purpose. In such a system, use is made of contact-making pads let into the road surface and the arrangements are such that the passing of a vehicle over the pad when in receipt of the "go" signal extends the right of way for a period sufficient to ensure its safe passage over the crossing. For ordinary crossings the period allowed is generally of the order of eight seconds or somewhat less, and this has become known as the vehicle interval. A stream of vehicles following each other at intervals of less than eight seconds would therefore extend the right of way up to a predetermined maximum period.

Considering now an isolated vehicle passing over the crossing, it will be seen that the safe crossing period resolves itself into the sum of an eight-second vehicle interval plus for example a four-second amber or other warning period which precedes the signal change. On particularly wide crossings carrying a considerable volume of relatively slow moving traffic, the minimum safe period which can be allowed is often in the neighborhood of sixteen to eighteen seconds and, with the ordinary method of working, to cater for this means an increase in either the vehicle interval or the cautionary period. A sufficient increase in the vehicle interval is out of the question, since it would seriously reduce the efficiency of the controller by allowing widely scattered traffic to repeatedly run the controller up to the maximum period. An increase in the cautionary period is also undesirable if it is to apply also to the traffic on the opposite phase which is awaiting the "go" signal.

The present invention overcomes the above objections by absorbing the additional time required in what is in effect a double cautionary period, although the cautionary period for each phase is no longer than that which is considered normal. Thus, cautionary periods may be given

consecutively to the two phases or alternately no cautionary warning signal need be given to traffic about to obtain right of way, the additional time required being absorbed in an all stop period which is also valuable as a pedestrian clearance period.

With these and other objects in mind, reference is had to the attached sheets of drawings illustrating one practical embodiment of the invention, and in which—

Fig. 1 shows diagrammatically the layout of the system as applied to a traffic intersection;

Fig. 2 is a circuit diagram of one form of traffic control system embodying the invention;

Fig. 3 is an enlarged view showing certain parts of the system of Fig. 2 which relate to the present invention;

Fig. 4 is a chart illustrating the position of the various circuit breakers which form a part of the operative control;

Fig. 5 is a plan view of a switch operating or timer mechanism;

Fig. 6 is an end view of the apparatus as shown in Fig. 5; and

Figs. 7 and 8 are transverse sectional views taken respectively along the lines 7—7 and 8—8 and in the direction of the arrows as indicated in Fig. 5.

Referring primarily to Fig. 1, it will be seen that the invention has been illustrated in connection with a traffic intersection involving lanes identified as "A" Street and "B" Street. A unitary signalling means 10 is provided in a position such that the signal indications will be visible to traffic approaching the intersection over these lanes. In advance of the intersection and in each lane there are provided traffic actuated elements 11 and 12 which connect with a control or timer mechanism 13 by means of which the operation of the signalling means 10 is regulated.

This signalling means—as will hereinafter appear—includes for each traffic lane visual signal indications for the according of right of way, the interrupting of right of way, and for a cautionary indication. In accordance with common practice, these indications may be green, red, and amber, respectively. However, this is merely for the purpose of illustrating one preferred embodiment of the invention, and might be varied in accordance with local requirements either by way of consolidating or substituting another indication for the one prevailing in the present embodiment. Likewise, while the invention has been illustrated with a traffic control system at the point of intersection of two traffic lanes, it

is obvious that the system might be enlarged or modified so as to control traffic on any number of lanes, and likewise the invention might be applied (as will hereinafter be apparent) to a fixed timer system.

Thus, referring to Fig. 2, it will be noted that the controls 11 and 12 have been shown in the nature of switches, and these switches are preferably of a pressure operated type such that, when traffic moves over them, a closing of the circuits controlled thereby will follow. A source of alternating electric current supply is connected to leads 14 and 67, and the first of these leads is extended and connected in parallel to the switches 15 11 and 12. Extending from the switch 11 is a lead 16 which connects with a relay 17, the latter controlling armatures 18 and 19. The latter armature is engageable with a contact coupled to a branch of lead 16, and the former, when in attracted position, engages a contact coupled to the branch 14. Likewise, the second contact of switch 12 is connected to a lead 20, so that when the switch is closed, the relay 21 will be energized to attract armatures 22 and 23. The opposite side 25 of the relay is coupled to a lead 24 interconnecting relays 17 and 21 and extending to the lead 61. Armature 22, when in attracted position, engages a contact extending from a branch of the lead 14, while armature 23, in a similar position, engages 30 a contact associated with lead 20.

Now referring to Figs. 5 to 8, it will be noted that a timing apparatus is employed which may include an electromagnet 25 which serves to retract an armature 26. The latter has coupled to 35 it a link 27, to the upper end of which a pawl 28 is secured. A stop 29 may limit the movements of this pawl in cooperating with the teeth of an annular ratchet 30. A return movement of this ratchet is prevented by a spring-pressed pawl 31, 40 and the link 27 is pivotally connected to one end of a lever 32, the opposite end of which is spring retracted as at 33, and the body of which is rockingly mounted upon a shaft 34. Thus the armature 26 is normally maintained in projected condition incident to the spring 33, and upon being energized is retracted to cause the pawl 28 to override one tooth of the ratchet, this resulting upon deenergization of the electromagnet, in the pawl shifting upwardly under the influence of the 45 spring 33, thus serving to rotate the ratchet 30 and the shaft 34, which latter, for this purpose, is affixed to it. Arranged in the path of movement of the outer end of the lever 32 is a switch 35, which may include spring arms mounting contacts from which leads 36 and 37 extend. As a 50 consequence of this construction, it is obvious that each time the electromagnet 25 is energized, the lever will engage the switch to cause a closing of the circuit between these leads.

As illustrated, the shaft 34 may be mounted for rotation between spaced standards 38, and these standards additionally support between them a series of switches identified in these figures under the general number of 39. The switches are operated by cams 40 secured to the shaft 34, and each of the switches shown in Figs. 7 and 8 may 55 include spring arms, mounting contacts and engageable by the portions of the cams to close and open the switches during predetermined phases of 60 a rotation of the shaft. At this time it will additionally be noted that the ratchet 30 may, for example, include eighteen teeth, and that each cam may have three operative portions for engagement, not alone with switches overlying the cam, 65 but also underlying the same. In this manner, if,

for example, only six operative movements of the cam shaft are necessary to complete one cycle of the apparatus, it will not be necessary to rotate the shaft through 360 degrees, but instead a mere rotation of 120 degrees will suffice to complete the cycle. Thus the rotation of the cam shaft by a pawl and ratchet mechanism will present no difficulty, and also by arranging the switches and cams as shown, an extremely compact and unitary apparatus is presented, in which each cam— 10 if desired—may operate any proper number of switches.

Now returning to a consideration of Fig. 2, it will be observed that certain of the cam operated switches have been identified as at 41 to 46 inclusive. With the parts in the positions shown in this figure, it is to be assumed—as will hereinafter be brought out—right of way exists in favor of "A Street" and is interrupted to traffic traversing "B Street". Thus a closing of switch 11 causes an energization of relay 17, with a consequent attraction of armatures 18 and 19, and due to the fact that switch 41 is closed, it will be apparent that the attraction of armature 19 locks relay 17 in, despite the fact that the switch 11 was only closed by, for example, the transition thereover of a vehicle. A series of resistances of different values are identified at 47 to 52 inclusive, and a circuit through any one of these resistances may be closed from the D. C. supplying lead 15 through the condenser 53 to the common return lead 14 by a series of switches 54 to 59 inclusive. These switches are operated by the cams mounted upon the shaft 34, and thus various switches will be closed at different phases in the operating cycle. In the position illustrated switch 56 is closed, and thus current will be fed to the condenser 53. A flash tube 60 of the neon type is in series with a relay 61, this tube being in shunt with the condenser 53 by having one of its 40 terminals connected with a lead common to the condenser, the relay being connected through leads 62 and 63 with switch 42, which in the example given is closed, and thence through the armature 18 to the lead 14. The condenser 53 has a capacity in excess of the critical voltage of 45 the tube 60. The value of the resistances 47 to 52 is carefully apportioned to the tube and condenser characteristics so that, according to the resistance through which current is being fed to the condenser, different and properly timed intervals will elapse before the condenser voltage reaches a sufficient point that the tube becomes conducting. Obviously, upon the operation of the tube 60 the relay 61 will function, so that its armature 63 will be energized to close the circuit through electromagnet 25 by virtue of the fact that this electromagnet has connected to it leads 64 and 65, and, of course, assuming that the latter leads are coupled (in a manner hereinafter 50 brought out) with a source of electrical current supply. In this manner it will be obvious that each time the tube 60 flashes the cam shaft 34 will be advanced one position, to thus close or open certain of the switches 41 to 46 and 54 to 59 inclusive.

At the present time the purpose of switch 35 will become apparent, in that it is arranged in shunt with the condenser 53, it being noted that a resistance 66 is preferably interposed in the 70 lead 37 so that a non-sparking but short-circuiting path is provided for the condenser each time the electromagnet 25 is energized. As a consequence, any tendency of the condenser to retain part of its charge will be counteracted, 75

and each time this condenser reaches the critical voltage of the tube 60 and causes the latter to become conducting the switch 35 will be closed to dissipate any residual charge of the condenser which might cause an improper functioning of the apparatus.

Reference is now had to Fig. 3 in which part of the structure specifically shown in Fig. 2 has been identified under the legend "Timing device", it being observed, however, that the relay 61 and the electromagnet 25 and also the signal elements, switches 75—81 and relays 82 and 83 are shown beyond such unit. These elements are also shown in Fig. 2 in connection with an embodiment of a traffic actuated type of signal timing device. In this view the numeral 67 indicates one power supply lead, and 68 the second lead. The latter may be directly connected to signal elements 69 to 74 respectively, all of which form a part of the signal generally indicated at 10. The elements 69 may provide a right of way indication in favor of "A Street", while element 72 may similarly provide for indication in favor of "B Street". Elements 70 and 73, respectively, may provide caution indications in favor of "B" and "A" Streets, while, finally, elements 71 and 74 may provide for an indication of interruption of right of way to these two traffic lanes. Cam actuated switch elements of the nature shown in Figs. 5 to 8 are identified by the reference numerals 75 to 80 inclusive, and it will additionally be observed that a similarly operated and constructed switch 81 is furnished, the purpose of which will be hereinafter brought out. Moreover, relays 82 and 83 are provided, the first, when energized, serving to attract switches 84 to 89 inclusive, while the second controls the position of the switch 90. In connection with relays 82 and 83 it will be noted that they may be shunted by rectifiers 91 and have associated with them condensers 92 so as to operate in a satisfactory manner in connection with alternating current. Obviously, however, relays of a different type not requiring this associated structure may be employed.

Attention is now invited to Fig. 4, in which there has been charted the closed position of the several switch elements 41 to 46, 54 to 59, and 75 to 80, the corresponding reference numerals having been applied adjacent the left hand edge on this chart. As will be noted, six positions are indicated in this chart, and this corresponds to the number of advances made by the shaft 34 before the latter completes one cycle. The heavy lines indicate a closed condition of the switches, the identifying numerals of which are arranged as afore stated.

The purpose of the foregoing construction and the cooperation of the parts will be best understood by considering the operation of the apparatus through one complete portion of a cycle. With the parts in the position shown in Figs. 2 and 3, it is to be assumed that the shaft 34 occupies a position identified in the chart of Figure 4 under C. In this position, as will be clear from the chart, switch 75 is closed to energize the element 69, and thus accord right of way to "A Street". Switch 77 is also closed to energize element 71 to interrupt right of way to "B Street". Switch 81, which is connected in circuit with the electromagnet 25 through armature-switch 90 and is in shunt with relay 82, is closed in all positions except those corresponding to the cautionary indication periods, i. e.,

positions A and D as shown in the chart of Fig. 4, so that except at these times relay 82 and therefore relay 83 cannot be energized. If it is now assumed that right of way is called from "A Street" to "B Street" by the passage of a vehicle over either of switches 11 or any equivalent operation of these traffic actuated controls, it will be obvious that, as afore brought out, the tube 60 will flash so as to operate relay 61, which thereupon, by its armature-switch 63, energizes 10 electromagnet 25. The shaft 34 is thus stepped into position D (Fig. 4) where switch 79 is closed to energize the signal element 73, while element 69 is de-energized incident to the opening of switch 75. In this position of the parts, however, switch 77 remains closed, and thereafter element 71 of "Street B" remains energized. This condition prevails until the expiration of the timing period (for example, four seconds), after which the relay 61 again operates so as to 20 again close the circuit through electromagnet 25. Owing to the opening of switch 81 in position D, the relay 82 may be energized and accordingly, upon the operation of the armature-switch 63, this relay operates in series with the electromagnet 25 and is of sufficiently high resistance to prevent the operation of the latter. This results in a discharge of the condenser 53 through tube 60 without operation of the electromagnet 25 and consequently movement of the camshaft 30 out of position D does not occur and the cam operated switches remain unchanged in this position. However the condenser 53 begins to charge again. In the meantime relay 82 operates and attracts the armature-switch 89, thus 35 providing a circuit for relay 83. Due to the attraction of armature-switches 86—87, the element 73 is de-energized and element 70 is energized. During this interval armature-switch 88 is attracted to cause a simultaneous energization of elements 71 and 74, so that the indication interrupting right of way prevails. The effect on the signalling unit 10, therefore, is that the cautionary indication of "A Street" is inoperative and interruption to right of way only is 40 indicated on this street, so that traffic thereon is now stopped while on "B Street" the cautionary indication is displayed in addition to interruption of right of way. This prepares traffic in the latter street to restart. It will be noted that 45 while relay 82 is energized and armature-switch 63 is still closed, relay 83 is shunted by armatures 89 and 90, lead 64, coil of solenoid 25, lead 65, armature 63 and lead 68. When armature-switch 63 is released thus interrupting this circuit shunting relay 83, relay 83 may be energized and operates in series with relay 82 and by means of the armature 90 again connects electromagnet 25 directly to the current supply. Since the cam shaft has not moved from position D during this sequence of operation, a further cautionary period is now timed (for example, four seconds), at the end of which energization of the electromagnet 25 occurs, which operates through armature-switch 90, to advance the cam shaft into position E. In this position the switch 81 is again closed so that relays 82 and 83 are de-energized and element 74 is now energized directly through the switch 80 and the right of 50 way indicating element 72 is energized by virtue of the fact that the switch 78 is closed. A similar sequence of operation takes place when the right of way is subsequently transferred from "B Street" to "A Street" and the circuit opera- 75

tions which take place will be readily followed from what has already been said.

As a consequence of this construction a double cautionary period is introduced between each change of signals, although the visible cautionary period to the respective streets is no greater than normal. If the arrangement is to be such that amber signals are given only to traffic losing the right of way, either one or both of switches TA and TB is opened and the operation of relay 82 will be effective in de-energizing the cautionary indicating element as already explained, but the armature switches 86 and 87 which transfer the lighting circuit to the cautionary element of the other street will in each instance be left unconnected if the corresponding one of switches TA and TB is open.

Obviously the most common and in certain respects the most desirable method of signalling is that provided by means of colored lenses, lamps or reflectors, green lights, amber lights, and red lights, to respectively indicate right of way, caution, and interruption to right of way. However, any desired substitute signalling arrangement might be provided. In addition, while in the present instance the cautionary phases or periods are equal, it is obvious that this need not necessarily be the case, and, as, afore brought out, while the present invention has been exemplified in connection with a traffic controlled signalling system, it might equally well be employed in association with a fixed timing system.

The full details of the system which may be employed have, of course, not been shown in Fig. 2, in view of the fact that the vehicle actuated controls, minimum, re-setting, and maximum timing expedients, etc. already form the subject matter of patents such as British Patents 299,040 and 355,741 for example. Thus, except in so far as hereinafter claimed, this portion of the system forms no part of the present invention, and is merely included to the extent shown for the purpose of exemplifying one operative form of apparatus. It is obvious where the present invention is included in a fixed time system, any desirable timer mechanism might be employed. If it should be desired to utilize substantially the same apparatus described in this specification, this might be done by simply eliminating the resistor 83 and permanently closing or shunting the switches 11 and 12.

Regardless of the type of system in connection with which it is utilized, it will be understood that simply by the addition of, for example, switch 81, the relays 82 and 83, as well as the structures associated therewith, an ordinary system may embody the benefits of the present invention, it being moreover apparent that numerous changes of construction and rearrangement of the parts might be resorted to without in any case departing from the spirit of the invention as defined by the claims.

In this connection it will be appreciated that although the embodiment of the invention illustrated in the drawings and described in the specification discloses a camshaft and cooperating cam contacts for controlling the signal circuits, and the term "camshaft" is used in the claims, the invention will be understood not to be limited to a camshaft type of construction but that a drum and contact segment or contact disk and brush type of construction or any other of the familiar types of cyclic circuit controlling devices could be employed without departing from the spirit of the invention.

Having thus fully described the invention, what is claimed as new and desired to be protected by Letters Patent is:

1. In a signalling system having signalling circuits including signals adapted to display different signal indications, a signal control apparatus comprising switches forming a part of said signalling circuits for operating said signals, a cam-shaft for operating said switches and having a plurality of positions thru which it is adapted to be operated cyclically, and time controlled means for normally operating said shaft from one position to another in its cycle at certain time periods so as to cause said switches to be operated to cause the display of such signal indications successively in a corresponding cycle, a relay in said system, means operated by said cam-shaft at a predetermined position in its cycle to operably connect said relay to said time controlled means for operation by the latter at completion of its time period at said position and so as to render said time controlled means ineffective to operate said shaft from said predetermined position, a switch operated by said relay and connected in series in one of said signalling circuits to cause when operated a change of signal indication from that which is caused by the operation of the signal control apparatus, and means operated by said relay to render said time controlled means again effective to normally operate said cam-shaft from said position on completion of a further time period.

2. In a signalling system having signalling circuits including signals adapted to display different signal indications, a signal control apparatus comprising switches in said signalling circuits for controlling the same, a cam-shaft for operating said switches and having a plurality of positions thru which it is adapted to be operated cyclically to provide a corresponding cycle of signal indications, means including a solenoid operative for driving said cam-shaft from one position of its cycle to another, and a timing device for normally operating said solenoid intermittently, a relay having a coil connected to said solenoid, means operated by said cam-shaft at a predetermined position in its cycle to cause operation of said relay by said timing device at said position and to render said solenoid ineffective to be operated by said device at said position, a switch operated by said relay and connected in series in one of said signalling circuits to cause when operated a change of signal indication, and means controlled by said relay and said timing device for rendering said solenoid again effective to normally operate said cam-shaft after a time period of operation of said relay.

3. In a signalling system having signalling means adapted to display different signal indications, a time controlled switching mechanism including switches adapted to be connected to said signalling means to operate the latter, a cam-shaft for operating said switches to so connect them successively to said signalling means and time controlled means for operating said cam-shaft cyclically to cause the display of said signal indications in a corresponding cycle, said system including a relay having a coil connected to said time controlled means to be energized thereby and having a switch operated by energization of said coil said switch being arranged in series with one of said first named switches and opened while said coil is energized to interrupt its connection to said signalling means, said relay when energized operating its switch to cause

5 a change of signal indication, and circuit means including a further switch operated cyclically by said camshaft and said circuit means in shunt across said relay coil normally to prevent such energization of the latter by the time controlled means except at certain points in its cycle at which the switch is open to permit such energization.

10 4. In a signalling system having signalling circuits including signals adapted to display different signal indications, a signal control apparatus comprising switches in said signalling circuits for controlling the same, a camshaft for operating said switches and having a plurality of positions through which it is adapted to be operated cyclically to provide a corresponding cycle of signal indications, means including a solenoid operative for driving said camshaft from one position of its cycle to another, and a timing device for normally operating said solenoid intermittently, a relay having a coil connected to said solenoid, means operated by said camshaft at a predetermined position in its cycle to cause operation of said relay by said timing device at said position and to render said solenoid ineffective to be operated by said device at said position, and means controlled by said relay and said timing device for rendering said solenoid again effective to normally operate said camshaft after a time period 30 of operation of said relay determined by said timing device.

35 5. In a signalling system having a plurality of circuits including signals for displaying different signal indications and a time controlled switching mechanism for energizing said circuits to operate said signals sequentially, said mechanism including switches in said signalling circuits, a camshaft for operating said switches sequentially and means including a solenoid for intermittently operating said camshaft when intermittently energized, and a time controlled switch means connected to said solenoid for normally intermittently momentarily energizing said solenoid, said system including a relay having a coil in series with said solenoid and time controlled switch means, and a further switch means operated by said camshaft and connected to normally shunt said relay coil to prevent its energization and to render said solenoid effective to be energized by said time controlled switch means during a part of the cycle of said camshaft, said switch means being opened by operation of said camshaft in another part of its cycle to render said solenoid ineffective and to render said relay coil effective to be energized by said time controlled switch means, a switch means operated by said relay, a second relay operated by operation of said last named switch means, and a switch means operated by said second relay to connect said solenoid to said time controlled switch means independently of the first relay so as to render said solenoid effective to be again operated by the next intermittent operation of said time controlled switch means.

60 6. In a traffic control system for interfering traffic lanes and having individual electric stop,

go and caution signals adapted to be energized to be displayed in said lanes for the control of traffic, a cyclic step by step switching device having a plurality of steps through which it is adapted to be operated to energize said signals 5 to display the latter successively in said lanes, a timing device normally connected to said switching device for intermittently stepping said switching device at predetermined time periods to determine the time intervals of display of said indications, said switching device being arranged at one step in its cycle normally to display said caution signal to one of said lanes prior to the display of a stop signal in said one lane and of a go signal to another lane in the next step, and 10 means including a relay arranged to be connected by said cyclic switching device at said one step in its cycle to render said timing device ineffective to operate said cyclic switching device and effective to operate said relay at the completion 15 of the normal time period of said timing device in said one step, means operated by said relay to extinguish display of the caution signal in said one lane and to cause display of the caution signal to said another lane, and further means operated 20 by said relay for rendering said timing device effective during the display of said last mentioned caution signal to step said switching device at the completion of its next timing period whereby said timing device is employed successively to time 25 30 the two recited caution signal displays in one step of said cyclic switching device.

35 7. In a traffic control system for interfering traffic lanes and having individual electric stop, go and caution signals adapted to be energized to be displayed in said lanes for the control of traffic, a cyclic step-by-step switch device having a plurality of steps through which it is adapted to be operated to energize said signals to display the latter successively in said lanes, a timing device normally connected to said switching device for intermittently stepping said switching device at predetermined time periods to determine the time intervals of display of said indications, said switching device being arranged at one step in 40 its cycle normally to display said caution signal to one of said lanes following display of said go signal in said one lane in the preceding step and while a stop signal is being displayed to another lane, and means including a relay arranged to be connected by said cyclic switching device at said one step in its cycle to render said timing device ineffective to operate said cyclic switching device and effective to operate said relay at the completion of the normal time period of said 45 timing device in said one step, means operated by said relay to extinguish display of the caution signal in said one lane and to cause display of the stop signal in said one lane as well as in said other lane, and further means operated by said relay for rendering said timing device effective during the display of said stop signals to both lanes to step said switching device at the completion of its next timing period.

50 55 60 65 DENIS WRIGHT.
